UNITED STATES PATENT OFFICE.

MARY E. FRANCISCO AND JOSEPH FINIS MARTIN, OF SAN DIEGO,
CALIFORNIA.

EXHIBITING-BOX.

SPECIFICATION forming part of Letters Patent No. 739,662, dated September 22, 1903.

Application filed April 8, 1903, Serial No. 151,567. (No model.)

To all whom it may concern:

Be it known that we, MARY E. FRANCISCO and JOSEPH FINIS MARTIN, citizens of the United States, residing at San Diego, in the county of San Diego and State of California, have made certain new and useful Improvements in Exhibiting-Boxes, of which the following is a specification.

Our invention is an improvement in boxes, and especially in exhibiting-boxes designed for use in holding dates and other articles of merchandise which it may be desired to protect and to which access may be conveniently had from time to time; and the invention consists in certain novel constructions and combinations of parts, as will be hereinafter described and claimed.

In the drawings, Figure 1 is a perspective view of our invention with the sliding sash lowered and the apron turned out to form a shelf for use in handling the dates. Fig. 2 is a vertical section of the box with the sliding sash raised and the apron adjusted upon the top of the box, and Fig. 3 is a cross-sectional view on about line 3-3 of Fig. 2.

The box A has a bottom B, sides C, back D, and top E, is open at the front, and is provided at such open front with a guide-frame F, having grooves G, in which slide the sash H, the lower portion of the front or guide-frame F being glazed at I, such fixed glazing extending about one-half the height of the box, as shown in Fig. 2. In the construction shown the guide-frame may be secured to the front of the box by screws, (see J in Fig. 1.) The box is also provided with a false bottom K, carried on rods L, which extend outwardly through vertical slots M in the sides C and connected with battens N, arranged on the outer side of the sides C and provided with clamping-screws O, which may be tightened to secure the false bottom in any desired vertical adjustment to adapt the box for use with packages of dates or the like of different heights.

The sash H slides vertically in the guides G, and the apron P is hinged at one edge at P' to the upper edge of the sliding sash, so it can be turned over the top of the box, as shown in Fig. 2, when the sash is closed, and thus operate to hold the sash elevated, can

be turned out to the position shown in Fig. 1 to serve as a shelf in handling the dates or other commodity stored in the box, and can be turned up, as indicated in dotted lines 1, 55 Fig. 2, against the outer face of the guide-frame F, and by means of its clamping devices operate to hold the sliding sash in a position intermediate those shown in full lines, Figs. 1 and 2. As shown and as preferred, the clamping devices are in the form of flanges Q on the apron P and arranged to overlap the opposite sides of the guide-frame F and being sloped or beveled on their inner faces at Q' in order to clamp the guide-frame 65 when adjusted to the full-line position shown in Fig. 2. By thus sloping or beveling the inner faces of the flanges Q at Q' the apron may be clamped in place when adjusted to its several positions, as before described.

The inner edge of the apron may be beveled or sloped to bind against the front of the frame and hold the apron open when adjusted for use as a shelf.

Having thus described our invention, what we claim as new, and desire to secure by Letters Patent, is—

1. The improved box as described for use in holding dates and the like, comprising a box proper having its sides provided with the longitudinal slots, a false bottom, supporting-rods projecting from said bottom through said slots, a bar outside the box and to which said supporting-rods are secured, means for clamping the bar in connection with the box for holding the bottom in different adjustments, a guide-frame secured to the open front of the box and having a lower fixed glazed section, a sliding sash movable vertically in the guide-frame, and an apron hinged at one end 80 to the upper edge of the sliding sash, and foldable upon the top of the box, when the sash is closed or extending out to form a shelf when the sash is lowered, and lying in against the face of the guide-frame and sloped or beveled on its inner edge for engagement with the guide-frame in different adjustments of the apron, substantially as set forth.

2. The combination of a box for holding dates and the like, a sliding sash at the front of said box, and an apron hinged at one edge 90 to the sliding sash and arranged to be turned

upon the top of the box, when the sash is closed or extending out to form a shelf when the sash is lowered, substantially as set forth.

3. The combination of the box, guides for the sliding sash, a sash sliding in said guides, and an apron hinged at its inner edge to the upper edge of the sash, and formed on its inner edge to bind in engagement with the sash-guides in the different adjustments of the sash and apron, substantially as set forth.

4. The combination of a box for dates and the like, a sliding sash and an apron hinged thereto, and sloped or beveled on its inner edge, to bind upon the box when adjusted into engagement therewith, substantially as set forth.

5. A box for dates and the like having at its front a lower fixed closure or section, a sliding sash to close the upper portion of the front of the box, and an apron hinged in connection with the said sliding sash, substantially as set forth.

6. A box for dates and the like, provided at its open front side with a guide-frame having a lower section or closure, an upper sliding sash, and an apron carried by said sliding sash, substantially as described.

7. A box for dates and the like provided in its sides with vertical slots, a false bottom having supporting-rods projecting through said slots, bars connected with said supporting-rods, and means for securing said bars in different adjustments along the sides of the box, substantially as described.
